SUCTION CLEANER

Louis E. Segesman, Canton, Ohio, assignor to The Hoover Company, North Canton, Ohio, a corporation of Ohio

Application November 12, 1946, Serial No. 709,275

7 Claims. (Cl. 183—59)

1

This invention relates to suction cleaners and more particularly to a new and improved device of this type having incorporated therein a novel filter shaker mechanism.

The present invention employs the same general type of filter shaker mechanism as my pending application for Letters Patent Serial No. 599,147, filed on June 13, 1945, now Patent No. 2,498,098, granted February 21, 1950; but differs therefrom in several important respects. Thus, the present invention relates to a trigger release shaker mechanism which is primarily designed for manual operation rather than for foot operation. Another basic difference concerns the redesign of one of the cleaner supporting runners in such manner that it functions additionally as a remote control for the shaker.

It is therefore an object of my invention to provide a novel suction cleaner having a self-contained filter shaker mechanism of unique design. Another object is to provide a new suction cleaner construction in which certain parts thereof have multiple functions. A further object is to provide a simplified filter shaker which is rugged, economical to construct, simple in operation, requires little effort to operate and which is highly efficient. More specifically, it is an object of my invention to provide a tank type suction cleaner with a filter mechanism which is adapted to be cocked and released manually from a remote position by means of a specially constructed supporting runner for the cleaner. Still a further object is the provision of a filter shaker which can be conveniently operated while the filter is being emptied and without permitting dirt and fine dust to escape into the room.

These and other objects will become apparent upon reading the following specification and claims and the accompanying drawings showing a preferred embodiment.

Figure 1 is a side elevational view partially in section of a tank type suction cleaner incorporating the invention.

Figure 2 is a top plan view of the shaker mechanism per se.

Figure 3 is a perspective view of the cleaner with the end cap removed and with the cleaner in an upright position for bag emptying purposes.

My invention has particular application to tank type suction cleaners which may comprise an outer elongated casing 10 having a readily removable closure 11 at its right hand end and a semi-permanently attached closure 12 at its left hand end. These closures are provided with air ports 13 and 14, respectively, which are adapted to de-

tachably receive suitable cleaning tools and other devices, as is well known in the art. Opening 13 is an air inlet passage while opening 14 is an air discharge port.

5 Removable closure 11 is shown as fitting over the end of casing 10 in an airtight manner and may be detachably secured in place by one or more suitable clamping devices such as toggle clamps 15. A convenient carrying handle 16 is mounted along the upper side of the casing and, as shown, includes an electric control switch 17 for the cleaner.

Suitably mounted within one end of the casing is any preferred type of motor fan unit 18.

15 The dirt filtering unit may consist of any desired form of flexible air pervious material such as fabric bag 19. The open end of this bag is secured, as by clamping ring 20, to the inturned edge of a filter supporting annulus 21. A circular spider, not shown, may be mounted in the closed end of the bag and secured thereto as by split clamping ring 22. The central portion of a yoke 23 is detachably secured to the central portion of the spider, while its oppositely extending 20 arms 24 are pivotally attached to portions of the filter shaker mechanism which will be described 25 presently.

Referring now to Figure 2, it will be seen that the shaker mechanism comprises a generally T-shaped bed-plate 25 which may be spotwelded or riveted to the under side of casing 10 at a point beneath the filter bag. The leg of the T is U-shaped in cross-section and provides a guideway for slide member 26. An upturned member 27 on the slide projects through a slot 28 in the upper side of member 25 and forms a retainer for the bail 29 of the shaker mechanism.

Pivotedly supported in the upturned ends of the head of the T is a flat link 30 and a U-shaped link 31 which are pivotally connected at their upper ends to sides 24 of the yoke and in such manner that they move in parallel relation to one another. The ends of bail 29 are received in openings in the arms of U-shaped link 31. A pin 32 preferably serves as the pivot for the U-shaped link 31 and also as the supporting means for one or more torsion springs 33. One end of the torsion springs bears against the bight portion of U-shaped link 31 while the other bears against inturned flanges 34 on the T-shaped member and in such manner as to urge the links to rotate counterclockwise as viewed in Figures 1 and 2. These springs serve normally to maintain the walls of the bag under tension and, during operations of the shaker, as the driving

springs for tensioning the filter walls abruptly to dislodge dirt.

The device for cocking the bag shaker mechanism and for releasing it by a trigger-like action comprises a linkage located in part within the casing and in part without and having a common pivot pin 35 extending through casing 10. Interiorly of the casing an arm 36 is secured to pin 35 as by staking and carries a pawl 37 on its outer end biased to rotate counterclockwise by spring 38. The side of arm 36 serves as a stop for the lower end of the pawl and its opposite end 39 is so disposed as to engage a roller 40 mounted on slide 26 when arm 36 is rotated clockwise. Due to the relative positions of pin 35 and roller 40, it will be clear that, as arm 36 and pawl 37 are carried to the right as viewed in Figure 1, roller 40 and slide 26 will also be moved to the right until such time as end 39 of the pawl passes out of engagement with the roller. It will therefore be apparent that rotation of the arm serves to cock torsion springs 33, and finally, in a trigger-like action, to release slide 26 thereby permitting springs 33 to snap the walls of the filter to taut position very abruptly.

In order that the parts just described may be restored to their initial positions without effort on the part of the operator, I have provided a tension spring 41 having one end secured to a fixed abutment 42 and its other end connected to the pin serving as a pivot for pawl 37. As this spring rotates the arm counterclockwise, spring 38 allows the pawl to rotate clockwise sufficiently to by-pass roller 40.

Referring now to Figures 1 and 3, it will be seen that an arm 43, like arm 36, is fixedly mounted upon pin 35 so as to rotate therewith but is located exteriorly of casing 10.

The means for rendering the cleaner easily transportable about the room being cleaned comprises a pair of runners mounted upon the under side of the casing. These consist of a runner 44 permanently secured to the under side of the casing and a second runner 45 which is so attached as to be movable longitudinally of the casing. Thus, one end 46 of the runner is bent so as to have a portion lying against the under side of the casing and another portion forming a pivotal connection with the outer end of shaker arm 43. The opposite end 47 of runner 45 is also bent to have a portion lying against the under side of the casing and to be held slidably thereagainst by a guideblock 48. A stirrup 49 straddles end 46 of the runner as shown in Figure 3 and its opposite sides serve as stops for the shaker operating mechanism. That is to say, as viewed in Figure 3, the top side of stirrup 49 limits the counterclockwise movement of arms 43 and 36 while the lower side of the stirrup limits the clockwise movement of these two arms.

The operation of my invention is as follows: Normally the positions of the parts is as depicted in Figures 1, 2 and 3. Normally, torsion spring 33 tends to rotate links 30 and 31 counterclockwise so as to maintain the walls of the filter taut. Likewise, spring 41 retains runner 45 as well as arms 36 and 43 in the positions shown in the drawings. Thus, pawl 37 is located on the left hand side of roller 40 and in position to move slide 26 to the right so as to tension the filter drive springs 33 as soon as runner 45 is moved downwardly.

Assuming that the cleaner has been in operation for a period of time and that the operator desires to shake the filter, the first step is to up-

end the cleaner so that runner 45 is not in contact with the floor and so that its upper end 47 is accessible to the operator. The operator then grasps or pushes against end 47 of the runner so as to rotate arm 43. This action carries nose 39 of the pawl against roller 40 on slide 26 so as to move bail 29 and the links carrying yoke 23 toward closure 11 of the cleaner thereby further stressing torsion springs 33 and collapsing the filter bag. As arm 36 continues to rotate, the end of the pawl will ride past roller 40 allowing the torsion spring to snap the yoke 23 to the left thereby quickly and abruptly tensioning the side walls of the filter with the attendant dislodgement of dirt adhering thereto. As soon as the operator removes his hand from the end of the runner, tension spring 41 inside the cleaner moves the runner back to its initial position as spring 38 connected to the pawl permits the same to rotate sufficiently to bypass roller 40 on the slide. In this way, the parts are restored to their initial position ready for another similar cycle of operation. The shaker mechanism may be operated as many times as are found necessary to clean the filter thoroughly although a single operation of the mechanism disclosed has been found entirely sufficient under normal cleaner operating conditions.

The invention is of particular value when emptying the filter. This is accomplished by loosening clamp 15 and removing closure 11. The cleaner is then up-ended onto its open end with a sheet of paper or a dirt-receiving receptacle therebeneath. While the cleaner is thus held in airtight relation to the dirt-receiving surface, the operator simply presses down on the upper end of runner 45 as often as it found necessary to clean the filter thoroughly. Since the spring 41 restores the parts to their proper operating position as soon as the operator removes his hand, it is merely necessary for the operator to press down on the handle formed by the end of the runner and to remove it. As soon as the dust has settled inside the filter, the cleaner is tipped back upon the runners, the end closure is replaced and the cleaner is ready for operation.

It is to be noted that with the novel shaker mechanism herein described, the only opening required in the casing to accommodate the mechanism is that for pivot pin 35. It is a very simple matter to provide an airtight and dirt-tight seal at this point as is manifest.

While I have shown and described but one embodiment of my invention, it is to be understood that this is to be taken as illustrative only and not in a limiting sense. I do not wish to be limited to the specific constructions shown and described but to include all equivalent variations thereof except as limited by the scope of the claims.

Having thus described my invention what I claim is:

1. A suction cleaner comprising a cylindrical casing having a normally closed end and an open end, a removable end cap for closing said open end, a filter bag closed at one end and having an open end secured to the interior of said casing and in communication with said open end, filter shaker means connected to the closed end of said filter including a spring operable to maintain the walls of said filter taut at all times except when said filter is being shaken, means for collapsing said filter in opposition to said spring from the exterior of said casing comprising a

skid member underlying said casing along one side thereof for supporting said one side of the casing above a floor, said skid extending from a point near the open end of said casing to a point near the closed end thereof, means movably connecting said skid member to said casing, and means connecting said skid member to said means for collapsing said filter whereby said filter shaker means can be actuated by up-ending said casing onto said open end and manually moving the end of said skid member remote therefrom to collapse said filter in opposition to said spring.

2. A suction cleaner as defined in claim 1 wherein said filter shaker means includes a normally closed releasable connection, and means for opening said releasable connection when said filter has been collapsed to a predetermined extent by the manual actuation of said skid member whereby said spring snaps the walls of said filter taut abruptly to dislodge dirt therefrom.

3. A suction cleaner as defined in claim 1 wherein said means movably connecting said skid member to said casing is shaped to constrain the movement of said skid to a plane substantially parallel to the axis of said casing.

4. A suction cleaner as defined in claim 3 wherein said means movably connecting said skid member to said casing is shaped to constrain the movement of said skid member to a direction substantially parallel to the axis of said casing.

5. A suction cleaner as defined in claim 1 including means for normally holding said skid member stationary with respect to said casing except when said skid is being operated to shake said filter.

6. A suction cleaner comprising an elongated cylindrical casing having a discharge end and an inlet end normally closed by a removable end cap, a filter therein having a closed end and an open

end secured across said inlet end of said casing, manually operable shaker mechanism for dislodging dirt from said filter when said cleaner is up-ended onto the inlet end thereof including spring means connected to the closed end of said filter for maintaining the walls thereof under tension except when said shaker is manually actuated to dislodge dirt from said filter, means for collapsing said filter in opposition to said spring means including an elongated skid member connected thereto and extending along the exterior of said casing to a point adjacent the said discharge end, said casing being normally supported in a horizontal position on said skid, means movably connecting said skid member to said casing, and means for normally holding said skid stationary with respect to said casing.

7. A suction cleaner as defined in claim 6 wherein said shaker mechanism includes a normally closed releasable connection, and means for opening said releasable connection when said filter has been collapsed to a predetermined position whereby said spring snaps the filter taut abruptly to dislodge dirt therefrom.
